UNITED STATES PATENT OFFICE.

JOSEPH MATHISON, OF LYNN, MASSACHUSETTS, ASSIGNOR TO HIMSELF,
WILLIAM D. ALLEN, OF SAME PLACE, AND CHARLES B. LANCASTER,
OF BOSTON, MASSACHUSETTS.

METHOD OF SECURING BUTTONS TO MATERIALS.

SPECIFICATION forming part of Letters Patent No. 268,370, dated November 28, 1882.

Application filed March 18, 1882. (No model.)

To all whom it may concern:

Be it known that I, JOSEPH MATHISON, of Lynn, in the county of Essex and State of Massachusetts, have invented certain Improvements in the Method of Securing Buttons to Material, of which the following is a specification.

This invention relates to the fastening of that class of buttons composed of a head and an eye projecting therefrom to the material or article to which such buttons appertain.

The invention has for its object to provide an improved method of attachment, whereby a series or row of buttons of this class can be secured to a boot or shoe or other article by a single continuous thread or cord, each button being independently secured, so that if the thread should be severed at points between the buttons none of the fastenings would be affected.

To this end my invention consists in the improved method of attachment, which I will now proceed to describe and claim.

The accompanying drawings, forming a part of this specification, represent the different stages of the operation of securing a button by my improved method.

The same letters of reference indicate the same parts in all the figures.

In carrying out my invention, I hold a button, A, with its eye substantially parallel to the surface of the material B, to which the button is to be secured, as shown in Figure 1. I may here remark that I prefer to perform the successive operations hereinafter described by a suitable machine having a receptacle for the buttons, automatic means for feeding the buttons to the point where they are to be secured, said means being, for example, such as are shown in Letters Patent of the United States No. 252,117, issued to me January 10, 1882, and suitable mechanism for forming and interlocking the loops hereinafter described. I do not limit myself, however, to any special form of mechanism or means for carrying out my invention. The button being held as above described, I first draw through the material B and through the eye of the button a primary loop, C, which is of such length as to extend

considerably above the button. I next draw 50 through the material at a short distance from the loop C and from the same cord or thread a secondary loop, D, which I pass through the loop C, as shown in Fig. 3. I next tighten the primary loop so as to bring the eye of the button down upon the material, as shown in Fig. 5. Finally, I pass the secondary loop over the head of the button, as shown in Fig. 5, and tighten said loop, as shown in Fig. 6, thereby interlocking the primary loops and converting 60 them into a square knot, which, when its parts are drawn taut, effectually secures the button, so that when a row of buttons are attached in the manner described to a continuous cord or thread the parts of the thread between the 65 secondary loop, D, of one fastening and the primary loop of the adjacent fastening may be severed or broken without in any way affecting either fastening, each being independent of all the others. The fastening thus formed, 70 besides being independent, constitutes a comparatively stiff connection between the button and the material to which it is secured, causing the button to stand out conveniently from the material, instead of hanging loosely. It is 75 also economical in the consumption of thread. When the fastening is formed by a machine the loops C D will be drawn by a suitable needle, either hooked or having an eye, and the loop C will be bent, as shown in Fig. 2, by 80 a lateral movement of the needle, while the latter is raised, so that the loop D will be drawn through the loop C, as shown in Fig. 3, by the next upward movement of the needle.

I claim—

1. The improved method herein described of securing buttons to material, the same consisting in drawing a primary loop of thread through the material and through the eye of the button, then drawing a secondary loop 90 through the material and through the primary loop outside of the eye of the button, then tightening the primary loop, and finally passing the secondary loop over the button and tightening said loop, thereby forming a square 95 knot, as set forth.

2. The article or material and the buttons thereon, combined with a single thread having

two loops—viz., a primary and secondary—for each button, the primary loop passing through the eye of the button and around the secondary loop, and the secondary loop passing around the eye of the button, as set forth.

In testimony whereof I have signed my name to this specification, in the presence of two sub-

scribing witnesses, this 15th day of March, A. D. 1882.

JOSEPH MATHISON.
